John Polhamus.

Design for the handles of Spoons, Forks, &c.

Fig. 1

PATENTED
AUG 27 1867

Fig. 2.

Witness,

Charles L. Smith

Geo. T. Pinckney

John Polhamus

United States Patent Office.

JOHN POLHAMUS, OF NEW YORK, N. Y.

Design No. 2,772, dated August 27, 1867.

DESIGN FOR A FORK OR SPOON-HANDLE.

The Schedule referred to in these Letters Patent and making part of the same.

TO ALL WHOM IT MAY CONCERN:

Be it known that I, JOHN POLHAMUS, of the city and State of New York, have invented or produced a new and original Design for the Handles of Forks, Spoons, &c.; and I do hereby declare the following to be a correct description of the said design, reference being had to the annexed photograph of a spoon with the said design upon the handle.

Figure 1 represents the upper side of the handle and concavity of the spoon, and

Figure 2 is the opposite or back of the handle and convexity of the spoon.

The general outline of the end of the handle is composed of arcs of circles at *a*, and two lines of beaded work form the general ornamentation, the space between the beads being plain on one side, and on the other tessellated, as shown. The scroll-work at *b* forms an ornamental widening towards the end of the handle. The ribs running along the shank or body of the handle terminate, as shown, at *c c*, and ornaments *d* and *e* are introduced near the intersection of said beads. Towards the spoon (fork or knife) end the ribs or beads terminate on one side as scrolls, with a small pine-apple ornament at *f*, and on the other the beads "die down" to nothing, and a double-leaved scroll and pine-apple ornament is introduced, as at *g*.

What I claim, and desire to secure by Letters Patent, is—

The design, of the shape and configuration of ornaments shown, for the handles of forks, spoons, &c.

In witness whereof I have hereunto set my signature this twenty-second day of July, 1867.

Witnesses:

CHAS. H. SMITH,

GEO. T. PINCKNEY.

JOHN POLHAMUS.
